UNITED STATES PATENT OFFICE.

JESSE W. NICHOLS, OF CHICAGO, ILLINOIS.

CROWN-SEAL-CAP MACHINE.

1,194,869.

Specification of Letters Patent. Patented Aug. 15, 1916.

Application filed May 22, 1913. Serial No. 769,226.

To all whom it may concern:

Be it known that I, JESSE W. NICHOLS, a citizen of the United States, residing at Chicago, in the county of Cook and State of Illinois, have invented certain new and useful Improvements in Crown-Seal-Cap Machines, of which the following is a specification.

This invention relates to the retention in place within a closure cap or cover of a packing disk or gasket and, while susceptible of application to closures of diverse type, has to do and is herein described in connection with the manufacture of what is generally known as the crown seal cork or cap.

The invention has for its principal object novel means for securing the cork disk in place within the cap. Prior to the attachment of such closures to bottles the flanged corrugated cap is provided with an inserted packing disk usually of cork and some provision is required to be made for holding the disk in place. It has been proposed to interpose adhesive between the top of the cap and the cork and by heating and simultaneously pressing the disk into contact with the softened adhesive to effect an attachment between the disk and the cap. By my invention I avoid the disadvantage of having present an adhesive with the associated danger of deleteriously affecting the stored contents of the bottle and also reduce the expense of manufacture by doing away with the labor and mechanism necessary to the heating and pressing of the caps. I accomplish this result by indenting the caps marginally upon the edge of the inserted disk so as to lock the same in position with the cap.

In the accompanying drawing and in the following detailed description based thereon I set forth my improved method and two forms of mechanism for carrying out the same.

It is to be understood that the invention is capable of further modification without departure from the essence thereof or the sacrifice of its material advantages wherefore the drawing and description are to be taken in an illustrative and not in an unnecessarily limiting sense.

In the drawing—Figure 1 is a front elevation showing the essential portions of a machine embodying the invention; Fig. 2 is a fragmentary irregular section illustrat-

ing the operation of the machine; Fig. 3 is a similar view based upon modifications; and Fig. 4 is a side elevation partly in vertical section of a crown seal cap after passing through the machine.

Having particular reference to Figs. 1 and 2 of the drawing, the reference numeral 11 designates the base of the machine supporting a stationary annular member 12 within which is concentrically mounted for rotation a rotary member 13. The latter is provided with a peripheral groove 14 the bottom of which is formed with outwardly facing ribs or teeth 15 while the stationary member 12 is provided with an inwardly facing groove 16, the bottom of which is advantageously smooth. The walls of the two grooves may either be an integral portion of the members themselves, or they may be formed of plates secured at the rear and in front of the two members. Preferably, and as shown, the groove upon the inner face of the stationary member 12 does not extend entirely around the same but only through a small arc and is bounded in front by a plate 17 removably attached to the member 12 by screws 18. Pricking pins 19 are mounted for radial adjustment in the rim of the member 12 with their points 20 projecting inwardly from the bottom of the groove a slight distance. The opposed grooves 14 and 16 together form an arcuate channel having a width substantially the same as the exterior diameter of the crown seal cap 21, which caps with their inserted packing disks 22 are fed to the upper portion of the channel in any approved manner as from a feed chute 23. As the caps drop into the channel the corrugations 24, which are ordinarily found in the side walls thereof, engage with the ribs or teeth 15 after the manner of gear teeth and the caps are transported through the channel with the walls in rolling contact with the ribbed exterior face of the rotary member 13 and with the smooth interior face of the stationary member 12 and when passing the pricking devices 19 the points 20 of the latter indent the walls of the caps at intervals forcing the metal inwardly and forming prongs 25 which engage with the periphery of the cork disk 22 and effectually prevent the dislodgment of the disk by the interlocking engagement between the disk and the prongs.

In Fig. 3 is illustrated a substantial re-

versal of the arrangement, the adjustable pricking devices 19^a being mounted radially throughout the periphery of the rotary member 13^a while the stationary member 5 12^a is provided upon its inner face with the ribs or teeth 15^a. The operation in the two cases is substantially the same, the caps being transported through the channel and provided in their passage with the inwardly 10 projecting prongs caused by the upsetting of the metal by pins.

An insulating interlining is advantageously employed between the cork packing and the top of the cap. It may consist of a 15 paraffined sheet of paper to prevent chance contact between the stored liquid and the metal of the cap, or as another form of lining a suitable lacquer may be applied to the inner face of the cap before the packing 20 disk is inserted, in which case a lacquer should be employed which is chemically inert so that no action will take place between the lacquer and the metal, or between the lacquer and the liquid contents of the receptacle upon which the cap is used as a closure. 25 In many respects the employment of a chemically inert lacquer is more desirable than a separate distinct lining and some such insulating medium is always desirable 30 to effectually safeguard the cap and contents against injurious reactions.

I claim:

1. In a machine for securing a packing within a closure cap, means to indent the 35 wall of the cap into peripheral engagement with the packing, said means comprising two members concentrically mounted to provide an arcuate channel between portions thereof, one of said members being rotatable 40 and one of the members provided with radially disposed pricking elements, the channel adapted to receive the caps and transport the same therethrough in rolling contact with the opposed edge walls thereof, sub- 45 stantially as described.
2. In a machine for securing a packing disk within a crown seal cap, means to indent the wall of the cap to form spaced 50 prongs inwardly projecting into peripheral engagement with the disk, said means comprising two members concentrically mounted to provide an arcuate channel between portions thereof, one of said members being rotatable and one provided with radially 55 disposed pricking elements, the channel

adapted to receive the caps and transport the same therethrough in rolling contact with the opposed edge walls thereof, substantially as described.

3. In a machine for securing a packing 60 within a closure cap, means to indent the wall of the cap into peripheral engagement with the packing, said means comprising two members concentrically mounted to provide an arcuate channel between portions 65 thereof, one of said members being rotatable, one of the members provided with radially disposed pricking elements and the other with teeth facing toward the channel, the channel adapted to receive the caps 70 and transport the same therethrough in rolling contact with the opposed edge walls thereof, substantially as described.

4. In a machine for securing a packing 75 disk within a crown seal cap, means to indent the wall of the cap to form spaced prongs inwardly projecting into peripheral engagement with the disk, said means comprising two members concentrically mounted to provide an arcuate channel between 80 portions thereof, the inner one of said members being rotatable and one of the members provided with radially disposed pricking elements, the channel adapted to receive the caps and transport the same therethrough 85 in rolling contact with the opposed edge walls thereof, substantially as described.

5. In a machine for securing a packing 95 disk within a crown seal cap, means to indent the wall of the cap to form spaced prongs inwardly projecting into peripheral engagement with the disk, said means comprising two members concentrically mounted to provide an arcuate channel between portions thereof, the inner one of said 95 members being rotatable and provided with radially projecting teeth and the other member provided with adjustable radially disposed pricking elements, the channel adapted to receive the caps and transport the same therethrough in rolling contact with the opposed edge walls thereof, substantially as described.

In witness whereof I have hereunto attached my signature in the presence of two 105 witnesses.

JESSE W. NICHOLS.
